UNITED STATES PATENT OFFICE

171,492

HELMET

Walter T. Erickson and Matt J. Palmu,
Superior, Wis.

Application October 2, 1953, Serial No. 27,065

Term of patent 14 years

(Cl. D3—13)

To all whom it may concern:

Be it known that we, Walter T. Erickson and Matt J. Palmu, citizens of the United States, residing at Superior, in the county of Douglas and State of Wisconsin, have invented a new, original, and ornamental Design for a Helmet, of which the following is a specification, reference being had to the accompanying drawing, forming part thereof.

Figure 1 is a front perspective view of a helmet, showing our new design; and

Figure 2 is a rear perspective view thereof.

We claim:

The ornamental design for a helmet, as shown.

WALTER T. ERICKSON.

MATT J. PALMU.
